ABSTRACT: A lighting fixture having a removable glass cover pivotally linked to a wall mounted holder is disclosed. The pivotal linkage is in the form of a unitary rigid member preferably formed of a rigid but compressible synthetic resin such as nylon which has a forwardly extending portion removably fastened to the top wall of the glass cover and includes a spaced rearwardly extending flange and an intermediate portion joining the fastening section with the flange. The flange is insertable into a slot provided at the intersection of the top and front wall of the lamp fixture. The flange bears against the inner top wall and the bottom edge of the slot of the fixture while the intermediate portion bears against the front wall of the fixture which provides a cantilevered support of the cover in a first closed position. On rotation of the cover upwardly the flange pivots and rotates into engagement with the front wall of the fixture in a second open position. In the open position access to the sockets, bulbs and the inside of the cover is permitted.

LIGHTING FIXTURE

BACKGROUND OF THE INVENTION

1. Field of the Invention

The present invention relates to a lighting fixture having a hinged cover and more particularly this invention relates to a pivotal and detachable assembly of a glass diffuser cover to a wall mounted fixture back.

2. Description of the Prior Art

Lighting fixtures of the type which are typically mounted on bathroom walls above mirrors utilize a plurality of incandescent light sockets supported on a base which are covered with a decorative and light diffusing glass cover usually extending beyond the ends of the bulbs and holder. The cover is typically attached to the holder by means of a bolt extending through a hole in the front of the cover which is threaded into a support member or socket extending from the front wall of the holder.

The long cover, usually made of glass, must be carefully handled since it is both smooth and fragile. The removal and replacement of the cover requires the use of both hands, one to support and manipulate the holes in the cover over the threaded fastener and the other hand to insert or release the bolt. Furthermore, due to the inconvenience in removing the cover, the cover is usually only cleaned when removed to replace a bulb. However, on many occasions the dirt accumulation is excessive and the cover should be cleaned on a more regular basis. This is of more concern in institutional rest rooms where cleanliness of the room must be maintained to satisfy employees and the public.

OBJECTS AND SUMMARY OF THE INVENTION

It is therefore an object of this invention to provide a simplified and convenient manner of attaching a glass cover to a wall mounted lighting fixture.

A further object of the present invention is the provision of a pivotal linkage of a glass cover to a wall mounted holder permitting ready access to the bulb and the interior of the glass cover.

Yet another object of the invention is to detachably mount a glass cover on a linking connection between the cover and a lighting fixture holder.

These and other objects and many attendant advantages of the invention will become apparent as the description proceeds.

According to the invention the lamp comprises a wall mountable fixture holder having top and bottom walls joined to a front wall. The front wall is provided with at least one light socket and an elongated glass cover is adapted to extend over and in front of the socket. The cover is rotatably connected to the holder by means of a rigid unitary linking member having a forward section removably attached to the top wall of the cover and a rearwardly projecting flange insertable into a slot provided in the front wall of the housing. In a first closed position the flange bears against the inner top wall of the housing and on a upward rotation of the cover to a second open position the flange rotates toward and into engagement with the front wall of the housing.

The invention will now become better understood by reference to the following detailed description when considered in connection with the accompanying drawings.

BRIEF DESCRIPTION OF THE DRAWINGS

FIG. 1 is a perspective view of the assembled fixture of the invention partially broken away to illustrate details of the holder;

FIG. 2 is a cross-sectional view taken along the line 2-2 of FIG. 1;

FIG. 3 is a further view of the lamp of the invention with the cover in an open position;

FIG. 4 is an enlarged top plan view of the cover linking member of the invention; and

FIG. 5 is a front elevational view of the linking member of FIG. 4.

5 DESCRIPTION OF THE PREFERRED EMBODIMENTS

Referring now to FIGS. 1 to 3 the lamp includes a holder 10, an elongated glass cover 12 and a linking member 14. The holder 10 is in the form of a rectangular housing having a top wall 16 and a bottom wall 18 joined by a front wall 20. The holder is adapted to be mounted on a vertical wall by typical fasteners not shown.

At least one lamp socket 22 suitably a double socket receiving incandescent lamps projects forwardly from the front wall 18 of the holder 10. The socket may be connected to spring clips, not shown, which are inserted into a cross shaped aperture 26. The wires from the sockets extend into the hollow portion of the interior of the holder and are connected to cable wires, not shown, to provide power for the lamps 24. At least one L-shaped opening 31 is provided on the holder comprising a rectangular slot 30 formed along the top edge of the front wall 20 of the holder joined by a longer slot 32 formed in the front portion of the top wall 16 of the housing. The slot 30 is positioned to one side of slot 32 to form a wider portion and an oppositely disposed narrower extension 33. A plurality, usually two openings 31 are formed in holder 10 to provide additional support for cover 12. The extensions 33 of a pair of openings 31 may face the same way to provide removability of linking member 14. However, when the extensions 33 face the same way there is a tendency for the linking members 14 to unexpectedly leave the openings 31 when the cover 12 is rotated. Therefore, it is preferred to form the two openings 31 with the extensions 33 not facing the same direction. They may face in as shown or both may face outwardly.

The glass cover 12 also has a top wall 34 and a bottom wall 36 joined by a front wall 38 to form a hollow rectangular member extending over and in front of the lamps 24. Usually the cover extends past the lamps and holder to provide diffusion of all light emitted by the bulbs in a direction viewed by the observer. The top plate 34 of the cover 12 contains at least one aperture 40 for attachment of the linking member in a manner that will be subsequently explained.

The pivotal linking member 14 is a unitary body suitably formed of a rigid but somewhat compressible and self-lubricating resin, for example a polyamide such as nylon. Linking member 14 has a rearwardly extending flange 44 which is of a length longer than the length of slots 30 or 32. The edges 46 of the flange 44 may be rounded to facilitate insertion and removal of the flange from the slots. A narrower, intermediate portion 48 extends forwardly and downwardly from the flange 44 and is of a length preferably at least equal to the thickness of the top plate 34 of the glass cover 12. Two small prongs 50 extend forwardly from the top edge of the intermediate portion 48. Intermediate portion 48 has a length no greater than the length of slot 30 and is positioned in attachment to flange 46 such that the distance from the edge of the portion 48 to the opposite edge 46 of the flange is less than the length of larger slot 32.

A forwardly extending ledge portion 52 is attached to the bottom edge of intermediate portion 48. A threaded connector 54 is inserted in ledge 52 flush with the top surface thereof and the portion extending past the bottom surface of the ledge 52 is encapsulated in a sleeve 56 of plastic. A rib 58 is centrally provided along the bottom edge of the ledge 52 providing an additional length of supporting abutment against the front wall 20 of the housing 10. A thumbscrew 60 having a head 62 larger than the diameter of the aperture 40 in the top wall 34 of the cover has a threaded portion insertable into and through the threaded connector 54.

The fixture is installed by pulling a cable through the wall at a position near the desired location of the holder 10. The socket wires are pulled through the cross shaped apertures 26

and the spring clips of the double sockets 22 are inserted into the apertures 26. The wires are attached to the cable and the holder 10 is then secured to the wall. Lamps 24 are placed in the sockets 22.

The linking members 14 are then inserted in the openings 31. The top wall 34 of the cover 12 is then positioned over the ledge 52 of the linking member with the apertures 40 disposed over the threaded connectors 54 and with the prongs 50 engaging the edge of the wall 34. The thumbscrew 60 are inserted through the apertures 40 into the connectors 54 and are fastened fingertight. The assembly of linking members 14 and cover 12 are no longer removable from the holder 10 since the outer edges of the upper slot 32 bearing against the intermediate portion 48 of the linking member 14 prevent sideward movement in either direction.

In the downward closed position, the intermediate portion 48 and extending rib 58 are in abutment with the front wall 20 of the holder 10 and the top surface of the flange 44 is in abutment with the top wall 16 of the holder 10. The cover is then in firm and stable cantilevered connection with the holder 10. The downward forces are distributed between the flange abutment with the top wall, the support of the flange by the lower edge of slot 30 bearing against the bottom portion of the flange 44 and the front wall 20 of the holder bearing against the intermediate portion 48 and the rib 58. A portion of the weight of the cover is also supported by means of the bottom wall of the cover 36 pushing against the bottom portion of the front wall 20. The horizontal component of the force of the cover is compensated by the edges 46 of the flange 44 which bear against the front wall 20 and prevent the linking member 14 from being pulled out of the housing 10 when the cover 12 is closed.

When it is desired to clean the inside of the cover 12 or to replace a bulb 24 the cover is rotated upwardly 90° until the protrusions 50 abut the front edge of the slot 32. Protrusions 50 thus act to cushion and protect the glass from coming in contact with the metal portions of the holder 10. In the open position the flange 44 will rotate into abutment with the inner edge of the front wall 20 of the holder.

The lamp of the invention provides substantially simplified and safer assembling and handling. The plastic linking member cushions the glass cover and absorbs jarring forces during rotation or handling of the cover and thus substantially reduces damage. The linking member of the invention further completely eliminates the necessity for hand tools during removal or rotation of the cover, freeing both hands for handling the cover. Should the cover be broken, a new cover is readily replaced by bolting it to the linking member.

It is to be understood that only preferred embodiments of the invention have been disclosed and that numerous substitutions, alterations and modifications are permissible without departing from the scope of the invention as defined in the following claims.

I claim:

1. A lighting fixture including:
a holder member comprising a housing having bottom and top walls joined by a front wall;
a first slot formed in said front wall at the intersection with the top wall for receiving a linking member;
a second longer slot formed in the top wall joining said first slot;
means on said front wall for supporting at least one lamp socket;
a light transmitting cover having a top wall and a front wall disposed over said holder said top wall having an aperture;
linking means having a forward portion having a length smaller than said first slot and including a mechanical fastener inserted into said portion flush with the top face thereof, a rearward flange having a length longer than said forward portion and said second slot insertable into and rotatable within said first slot, said forward portion being joined to said flange such that the distance from an

edge of the flange to the far edge of the forward portion is less than the length of said second slot; and
means insertable through said aperture into said fastener for attaching the top wall of the cover to the forward portion of the linking means.

2. A lamp according to claim 1 in which said linking means comprises a unitary, rigid member formed from a synthetic plastic.

3. A lamp according to claim 2 in which said plastic unitary member comprises an enlarged flange section, a spaced, parallel, forwardly projecting ledge section having means for attachment to said cover and an intermediate section joining said flange and said ledge sections.

4. In a lamp fixture having an elongated translucent cover including a front wall and a top wall including a plurality of apertures and a wall mountable housing having a pair of oppositely facing horizontal L-shaped slots formed in the intersection of the front wall and the top wall of the housing, the combination therewith of a pair of pivotal linking members each comprising a unitary rigid member having:

a horizontal flange section insertable into and rotatable within each of said slots, the flange section being longer than said slots and a pair of first and second flange sections having opposite ends engaged by the edges of the respective slots to prevent sideways movement and removal from the slots when the members are attached to the cover;

a forwardly projecting horizontal ledge section spaced from the flange section having a mechanical fastener inserted in the ledge section flush with the top surface thereof and below one of said apertures for attachment of said ledge section to said cover by means of a removable bolt member; and

an intermediate vertical section joining each of said flange and ledge sections and having a length not less than the thickness of said cover.

5. A lighting fixture comprising:

a holder member for attachment to a horizontal wall including a housing having bottom and top walls joined by a front wall;

means on said front wall for supporting at least one lamp socket;

a pair of first horizontal slots formed in said front wall at the intersection with said top wall for receiving a linking member;

a second longer horizontal slot formed in said top wall joining each of said first slots, each of said second slots having one end coextensive with said first slot and each having a second end facing opposite ends of said housing;

a light transmitting cover having a top wall and a front wall extending over the front wall of said holder and socket; and

rotatable cover support and linking means comprising a pair of unitary rigid members having a rearwardly extending flange section, a forwardly projecting ledge section spaced therefrom for attachment to the top wall of said cover and an intermediate joining section having a length not less than the thickness of the top wall of said cover, said flange section being insertable into each of said second slots and bearing against the inner surface of the top wall of the housing to support said cover in closed position and being rotatable with said attached cover to an open position to engage the front wall of the housing to expose said sockets, said rearward flange having a horizontal extension larger than any of said slots and said forward portion being dimensioned to be disposed in said first slot and being joined to the rearward flange at a position such that the distance from an edge of the flange to the far edge of the forward portion is less than the length of said second slot and said ledge section being joined to said flange section by the intermediate joining section having an extension between said ledge and flange not less than the thickness of the top wall of said cover

whereby said linking means are not removable from said oppositely facing second slots by rotation or lifting motion when attached to said linking means.

6. A lighting fixture according to claim 5 in which each of

said linking means further includes at least one short prong extending from the upper end of intermediate joining section above the top wall of said cover for engaging and protecting of said cover during rotation into open position.
